US0D1076836S

(12) **United States Design Patent** (10) **Patent No.:** **US D1,076,836 S**
(45) **Date of Patent:** **** May 27, 2025**

(54) **MAINFRAME WITH INTEGRATED LID**

(71) Applicant: **Applied Materials, Inc.**, Santa Clara, CA (US)

(72) Inventors: **Michael R. Rice**, Pleasanton, CA (US); **Michael C. Kuchar**, Georgetown, TX (US); **Robert M. McAndrew**, Austin, TX (US); **Travis Morey**, Austin, TX (US); **Adam J. Wyatt**, Round Rock, TX (US); **Ofer Amir**, Half Moon Bay, CA (US); **Sushant S. Koshti**, Sunnyvale, CA (US); **Angela Rose Sico**, Round Rock, TX (US)

(73) Assignee: **Applied Materials, Inc.**, Santa Clara, CA (US)

(**) Term: **15 Years**

(21) Appl. No.: **29/828,766**

(22) Filed: **Feb. 28, 2022**

(51) **LOC (15) Cl.** **15-09**

(52) **U.S. Cl.**

USPC **D15/141**; D15/138

(57) **CLAIM**

The ornamental design for a mainframe with integrated lid, as shown and described.

DESCRIPTION

FIG. 1 is a top, front perspective view of a mainframe with integrated lid showing our new design;

FIG. 2 is a side view thereof;

FIG. 3 is an opposite side view thereof;

FIG. 4 is a front view thereof;

FIG. 5 is a rear view thereof;

FIG. 6 is a top view thereof;

FIG. 7 is a bottom view thereof; and,

(Continued)

FIG. 8 is another top, front perspective view thereof, shown in a used condition with unclaimed components attached thereto.

The broken lines shown in the figures are directed to unclaimed portions of the mainframe in FIGS. 1-8 and unclaimed components attached to the mainframe in FIG. 8 that form no part of the claimed design.

1 Claim, 7 Drawing Sheets
